[57] CLAIM

The ornamental design for a lowboy deck cabinet, as shown and described.

DESCRIPTION

FIG. 1 is a front elevational view of a lowboy deck cabinet embodying my design;

FIG. 2 is a top plan view of FIG. 1; and

FIG. 3 is a left end view of FIG. 1.

The side of the lowboy deck cabinet not shown is like the side shown while the rear is conventionally flat and unornamented.

FIG. 2

FIG. 1
